DESIGN FOR A SHOE

Arthur H. Tupper, New York, N. Y.

Application November 28, 1940, Serial No. 96,920

Term of patent 3½ years

To all whom it may concern:

Be it known that I, Arthur H. Tupper, a citizen of the United States of America, residing in New York city, county of New York and State of New York, have invented a new, original, and ornamental Design for a Shoe, of which the following is a specification, reference being had to the accompanying drawing, forming part thereof.

Fig. 1 is a plan view of a shoe showing my new design.

Fig. 2 is a side elevational view thereof.

I claim:

The ornamental design for a shoe, as shown.

ARTHUR H. TUPPER.
